US0D1045073S

(12) **United States Design Patent** (10) **Patent No.:** **US D1,045,073 S**
(45) **Date of Patent:** **** Oct. 1, 2024**

(54) **STOOL AND URINE SAMPLE COLLECTOR**

(71) Applicants: **Maxim Nesmiyan**, Sacramento, CA (US); **Rebecca Lundy**, El Dorado Hills, CA (US); **Shane Lundy**, El Dorado Hills, CA (US); **Briant Benson**, Placerville, CA (US)

(72) Inventors: **Maxim Nesmiyan**, Sacramento, CA (US); **Rebecca Lundy**, El Dorado Hills, CA (US); **Shane Lundy**, El Dorado Hills, CA (US); **Briant Benson**, Placerville, CA (US)

(73) Assignee: **Pediatric Medical Devices**, Rocklin, CA (US)

(**) Term: **15 Years**

(21) Appl. No.: **29/846,609**

(22) Filed: **Jul. 18, 2022**

(51) LOC (14) Cl. **24-04**

(52) U.S. Cl.

USPC **D24/123**
